DESIGN FOR A FIRE EXTINGUISHER

Frank C. Bishop, Atherton, and Aldus L. Hershey,
San Francisco, Calif.

Application March 3, 1941, Serial No. 99,290

Term of patent 14 years

To all whom it may concern:

Be it known that we, Frank C. Bishop and Aldus L. Hershey, citizens of the United States, residing respectively in the city of Atherton, county of San Mateo, and in the city and county of San Francisco, both in the State of California, have invented a new, original, and ornamental Design for a Fire Extinguisher, of which the following is a specification, reference being had to the accompanying drawing, forming part thereof.

Referring to the drawing:

Fig. 1 is a top plan view.
Fig. 2 is a front elevational view.
Fig. 3 is a side elevational view, and
Fig. 4 is a rear elevational view of a fire extinguisher showing our new design.

We claim:

The ornamental design for a fire extinguisher, as shown.

FRANK C. BISHOP.
ALDUS L. HERSHY.
